United States Patent Office

CHARLES B. GOODRICH, JR., OF BOSTON, MASSACHUSETTS.

Letters Patent No. 97,769, dated December 14, 1869.

IMPROVED SHUTTER-FASTENER.

The Schedule referred to in these Letters Patent and making part of the same.

I, CHARLES B. GOODRICH, Jr., of Boston, in the Commonwealth of Massachusetts, have invented a new and useful Improvement in the Mode of Fastening Window-Blinds, Shutters, and Doors in place, of which the following is a true specification, having reference to the accompanying drawings.

The common mode of fastening blinds is by a catch of iron, having upon the outer end a shoulder, into which the spring or hook upon the blind is caught. The other end tapers to a dull point or wedge, which is driven between the bricks, or into the wood.

The objections to this are that it works loose in use, it is difficult to drive, and is liable to be drawn out by heavy winds acting upon the blind.

My invention obviates all these objections.

I take a rod of iron, about one-third of an inch in diameter, and make upon one end a shoulder or other device, to engage with the hook-spring or other fastening-fixture on the blind.

I prefer the common catch inclining from the top of the shoulder to the base-line, as represented at Figure 2 in the drawings; but any form of catch adapted to the fixtures on the blind, can be used with my improvement.

On the other end of this rod I form a screw-thread.

The length of the rod must be adjusted to the depth of the penetration required.

I pass the rod through the brick, or the wood, or stone, of which the house is constructed, and make it fast by a nut screwed thereon.

To hold it the more firmly, I make a shoulder on the rod, where it will strike against the outside of the building.

I also insert a thin washer between the shoulder and the outside of the wall, against which the shoulder will bear and press it against the building.

I prepare bricks perforated through, with a hole fitted to receive said rod, and having on the inner side a space countersunk to receive said nut, and hold the same from turning when the rod is screwed into it.

For ordinary purposes, this hole is made through the middle of the brick, at right angles to the longest sides, and parallel with the bottom and top.

In building a house, the brick thus perforated, hav-

ing a nut in the countersink, should be so placed that the fastening-fixture on the blind will engage with the outer end of the rod, when inserted in the aperture.

The rod may then be inserted in the hole, and screwed up till the said washer or the shoulder is brought against the surface of the building; or the said rod may be inserted in the brick, and screwed up to its place before the brick is laid.

In wooden buildings the nut may be placed on the inside of the wood-work as aforesaid, or a longer screw may be cut upon the rod, and the same screwed directly into the wood.

For stone-work, I make the aperture in the stone or ashlar of the outer wall, or insert the rod in the mortar seam when in process of building.

The aperture is made by drilling, or by inserting in the clay a model or form in wood of the rod and nut, when the brick is moulded, and allow the same to burn out in burning the brick.

My catch may be brought nearer or projected further from the wall by means of the said washer-screw and nut at will.

In the accompanying drawings, the figures represent the improvement, as follows:

Figure 1, a front elevation or side view of the brick, with the aperture.

Figure 2, the rod with the shoulder-catch, washer-screw, and nut, all complete.

Figure 3, the brick in position, with the rod inserted, and the catch projecting from the front.

Figure 4, the brick when in position in the wall, with the nut attached, rear view.

I claim, and desire to secure by Letters Patent—

The combination of a catch-rod, constructed with a screw-thread on the inner end, and a catch on the outer end, with a brick perforated to receive the same, and a nut to secure the same, all substantially as and for the purposes described.

CHARLES B. GOODRICH, JR.
